United States Patent Office

Des. 197,039
Patented Dec. 3, 1963

197,039

ROTARY-WINGED AIRCRAFT

Malcolm S. Harned and Kenneth B. Amer, Los Angeles,
Calif., assignors to Hughes Tool Company, Houston,
Tex., a corporation of Delaware

Continuation of design applications Ser. No. 67,983,
Dec. 19, 1961, and Ser. No. 67,985, Dec. 19, 1961.
This application Apr. 25, 1963, Ser. No. 74,712

Term of patent 14 years

(Cl. D71—1)

FIG. 1

FIG. 2

FIG. 1 is a front perspective view of a rotary-winged aircraft, showing our new design;

FIG. 2 is a rear perspective view taken from the side opposite that shown in FIG. 1;

FIG. 3 is a front perspective view of a rotary-winged aircraft showing another embodiment of the design shown in FIG. 1; and

FIG. 4 is a rear perspective view taken from the side opposite that shown in FIG. 3.

This application is a continuation of companion co-pending applications Serial Numbers D. 67,983 and D. 67,985 both filed December 19, 1961.

The rotor blades are fragmentarily shown in the drawings for convenience of illustration. The dominant features of the design resides in the portions shown in full line.

We claim:

The ornamental design for a rotary-winged aircraft, substantially as shown and described.
